Application January 12, 1934, Serial No. 706,322
In Great Britain January 24, 1933

7 Claims. (Cl. 139—13)

This invention relates to circular looms, and has particular reference to the positioning of the shuttles within the warp shed.

In circular looms in which weaving takes place round the whole loom circle, and especially where close warp spacing is required as in the case of practically all textile fabrics, the weft inserting means remains totally enclosed on its two sides by the two sheets of warps. Moreover, when in order to produce the largest possible amount of fabric for any given diameter of loom, the warps proceed in a cylindrical manner from the warp supply to the woven fabric, the weft inserting means always remains totally enclosed within the warps so that in order to hold the weft inserting means stationary in relation to the warps force must be applied in some manner or other through the warps themselves. Over a long period of years, very many proposals have been made to this end, including electro-magnetic or other electrical devices and a large number of mechanical arrangements, which latter aimed at holding weft inserting means positively in place. Electrical devices, however, are particularly inconvenient and troublesome, and since with mechanical arrangements any force employed has to be applied through one or both sheets of warps, the danger is always present that the warps will be damaged, and in fact this is one of the main difficulties that prevented the adoption of circular weaving on any practical scale.

No satisfactory solution of these difficulties was available prior to that offered by the arrangement set out in U. S. Patent No. 1,626,411, and French Patent No. 577,713 which describes shuttle holding means that avoid danger of damaging the warps, these means comprising vane wheels passing through one sheet of the warps so as to engage in recesses in the shuttles. The vane wheels are rotated during operation of the loom so that slots between the vanes are continually presented to the warp threads in the sheet through which the wheels pass, and so permit the passage of the threads past the vane wheels, while allowing positive mechanical connection to be maintained with the shuttle. As described in the prior specifications, each vane wheel engages a freely rotatable roller mounted in the shuttle body and a curved recess in the shuttle body or a pair of such rollers mounted in a recess in the shuttle body, so that in either case there is a two-point engagement between each vane wheel and the shuttle. On the other side the shuttle is provided with a freely rotatable roller mounted opposite a circular race

within the inner warp sheet, this race and roller being situated at a level intermediate the two points of contact of the vane wheels with the shuttles. The race thus forms an abutment to withstand the thrust of the vane wheels.

It has been found, however, that the frictional engagement of the vane wheels with their corresponding recesses in the shuttle bodies in resisting the tendency of the shuttles to rotate with the warps, leads to some difficulties in practice, since wear takes place because of the rubbing between the wheels and the recesses, thus allowing the shuttles to become loose and even grinding the edges of the vanes, so that there is danger of the warp threads being cut in their passage through the vane wheels. Consequently, while the principle of maintaining firm contact with the shuttles by means of the vane wheels while letting the warps pass substantially uninterrupted solves one of the major difficulties of circular weaving, considerable practical difficulty has been encountered for the reasons mentioned.

According to my invention, this difficulty is avoided by arranging that the vane wheels positioning the shuttle within the warps and resisting the tendency of the shuttle and the warps to rotate together during weaving make rolling contact with pairs of rollers carried by the shuttle, means being provided to prevent the vane wheels making rubbing contact with the shuttle body, the danger of wear thereby being diminished. For example, the pairs of freely mounted rollers may be provided with flanges, preferably one for each vane wheel, the flanges being adapted to engage the vane wheels on the sides thereof towards which the shuttle is to be urged against the drag of the warp threads. In this manner the shuttle is accurately positioned in a fore and aft direction, the drag of the warp threads holding the flanges in contact with the vane wheels, while the vane wheels press upon the flanges and hold the shuttle against the action of the warp threads. Vertical and lateral positioning of the shuttle may be obtained by the provision of a further roller on the shuttle on the side opposite the vane wheels, and a circular race engaged by said roller, the roller rotating on a substantially vertical axis.

Preferably there are at least two vane wheels in connection with each shuttle so that the shuttle is held firmly not only in a vertical direction, but also in a fore and aft direction. One race-engaging roller is in general sufficient for each shuttle.

The invention will now be described in greater

detail with reference to the accompanying drawing, in which

Fig. 1 is a front elevation of a shuttle;
Fig. 2 is a vertical section of Fig. 1;

5 Fig. 3 is a view similar to Fig. 2 showing other features of construction and also a slight modification of shape existing between alternate shuttles;

10 Figs. 4 and 5 are sectional views to a larger scale of details of Figs. 1 and 2 respectively;

Fig. 6 is a plan view showing the mounting of two consecutive shuttles at the periphery of the loom;

15 Figs. 7 and 8 show in plan and side elevation one form of lubricating device; and

Fig. 9 shows in front elevation an alternative form of lubricating device.

Referring to Figs. 1-3, the shuttle comprises an upper plate 10 and an intermediate plate 11, 20 both being slightly curved and pointed at their front and rear ends similar to boats, the plates being connected together by a light but stiff bracket 12. To the underside of the plate 11 is secured a plate 13 forming in its upper half a frame 14 to support the shuttle-holding mechanism, and curving in its lower half to a foot 15, of which the under edge lies at the fell of the fabric. Across the frame 14 are arranged two vertical members 16 forming supports for two 25 horizontal spindles 17 rotatably mounted in ball bearings 18 in the members 16 and terminating in rollers 19. Each roller 19 is provided with a pair of flanges 20.

30 Disposed adjacent to each shuttle and outside the circle in which the shuttle lies is a shaft 21 carrying two pairs of vane wheels 22, the shaft being at a level between the two spindles 17. The wheels 22 are of such diameter as to bear with their peripheries against the body of the rollers 19 and are so spaced that each wheel bears against the rear (i. e., right-hand) face of one of the flanges 20.

35 At substantially the same level as the shaft 21 but on the opposite side of the shuttle lies a ring 45 23 whose edge bears against a roller 24 mounted between the spindles 17. The roller 24 is carried by ball bearings 25 on a spindle 26 secured on a cross-bar 27 extending between the members 16. The shuttle is thus engaged on one side by the 50 vane wheel contact made at the level of the spindles 17, and on the other side by the contact made by the ring 23, and is thus held securely in position with the plate 13 substantially vertical as shown in Figs. 2 and 3.

55 The face of the ring 23 is somewhat inclined, the roller 24 being inclined to correspond so as to produce a slight vertical component of the thrust between the ring and roller to assist in bearing the weight of the shuttle.

60 The arrangement of the upper and lower rollers 19 and the intermediate roller 24 provides a three level suspension resisting rocking of the shuttle about a horizontal axis. Further, the provision of the rollers 19 both before and behind the roller 65 24 provides a triple support resisting rocking of the shuttle about a vertical axis. At the same time, all contacts are made with members freely rotatable in the shuttle body, so that substantially rigid positioning of the shuttle is obtained with 70 little power consumption and reduced tendency to wear.

75 The wheels 22 should be very smoothly polished and made of metal highly resistant to wear, e. g. high-tension steel. The rollers 19 should be made of similar tough material.

The warp sheet at the outside of the shuttle passes through the slots in the vane wheels 22, while the warps on the inside of the shuttle pass between the ring 23 and the roller 24. In order to avoid damage to the warps at this point, the 5 ring 23 is preferably covered with a ring 28 of resilient material such as rubber, the depth of the ring preferably not exceeding that of the roller 24 so as to avoid danger of the warps being nipped.

The bracket 12 is provided with pressed-out 10 clips 29 to receive the spool 30, a movable clip 31 holding the spool firmly in place.

Weft is led from the spool through a slot 32 at the rear end plate 11 down to an eye 33 at the lower rear edge of the foot 15. A warp feeling 15 device 34 is provided at the front edge of the shuttle, the construction of the device shown being that described in U. S. application S. No. 655,561 filed 7th February, 1933.

The mounting arrangement offers an important 20 advantage in that by holding the shuttle in a very rigid manner within the warps, the pick density of the fabric can be rendered independent of the weight of the shuttle, since fabric and warps are 25 relieved of the necessity of supporting or guiding 30 the shuttle. Since, however, the shuttle is substantially entirely restricted from movement, its edge pressing a previously inserted pick positively into the fabric, so making the pick density a 35 function merely of the rate at which picks are 40 inserted and the rate of take-up. Consequently, the shuttle arrangement admits of the production of fabrics covering a wide variety of pick density. In addition, the diminution of shuttle vibration 45 enables the feeler 34 to be made very sensitive 50 in character.

As is shown by Figs. 2, 3 and 6, alternate shuttles have slightly different constructions, the left-hand shuttle in Fig. 6 (corresponding to Fig. 3) having its top plate 10 displaced outwardly so that 40 its point 35 lies outside the normal warp circle 36, while the plate 10 of the right-hand shuttle (corresponding to Fig. 2) is displaced inwardly so that its point 35 lies inside the circle 36. This arrangement facilitates passage of the shuttles 45 into the sheds which have commenced immediately in advance of the shuttle by shedding wheels or the like.

The shafts 21 and wheels 22 lying outside the 50 warp circle are conveniently accessible, the shafts 21 being driven by any suitable means (not shown) at a speed proportional to the speed of the loom. It will be understood that the shuttle 55 mounting is effective both with rotating warps and with rotating shuttles. In the one case, the 55 engagement of the wheels 22 with the right-hand faces of the flanges 20 resists motion of the shuttles under the action of the warps moving from left to right (see Fig. 6); in the other, the wheels 22 push the shuttles from right to left through the 60 warps.

The construction shown makes the shuttles relatively light in weight, so enabling rotating shuttles to be rapidly stopped or stationary shuttles 65 to be quickly brought to warp speed in the event of warp breakage or jamming being detected by the feeler 34. Suitable mechanism for this purpose is described in U. S. Patent No. 1,822,292.

Referring to Figs. 7 and 8, lubrication of the 70 wheels 22 is effected by means of a porous pad 37, e. g. of leather, pressed against the periphery of the wheel by means of a spring 38 carrying the pad from a support 39. Holes 40 permit lubricant to be supplied to the pad so that the edge of 75

the wheel making contact with the rollers 19 is lubricated.

Fig. 9 shows an alternative lubricating device in which a pad 41 mounted on a similar spring 42 is pressed against the face of the wheel 22 so as to apply lubricant to that part of the wheel which makes contact with the rear face of one of the flanges 20.

What I claim and desire to secure by Letters Patent is:—

1. In a circular loom employing rotatable vane wheels passing through the warps into engagement with a shuttle to position the shuttle within the warps, a lubricating pad, and means adapted to support said pad and press it against a vane wheel to lubricate the same.

2. A shuttle for a circular loom, said shuttle comprising two superposed boat-shaped plates, a light spool-holding bracket connecting said plates, a light, apertured plate secured below the lower plate, a frame in the aperture of said plate, horizontal bearings at different levels on said frame, two roller-carrying spindles mounted in the bearings, a substantially vertical bearing on the frame, and a roller mounted in said bearing and disposed between the two roller-carrying spindles.

3. A shuttle according to claim 2, wherein the light plate carrying the roller frame curves to form a foot below the frame, a guide-eye being mounted at the rear end of the foot.

4. A circular loom comprising a shuttle, two vane-wheel members mounted in spaced relationship on a common horizontal axis at one side of the shuttle, two pairs of flanged rollers mounted at two different levels in the shuttle for rolling engagement with each vane-wheel member, the flanges on the rollers preventing the vane-wheel members from making rubbing contact with the shuttle body, a circular race mounted adjacent the other side of the shuttle at a level between the levels of the flanged roller pairs, and a roller mounted on a substantially vertical axis in the shuttle to engage the said circular race, said roller being positioned between the two vane-wheel members, and said race being provided with a resilient covering to avoid damage to the warps passing between the race and the said roller.

5. A circular loom comprising, in combination with a source of supply of warps, a shuttle, pairs of rollers carried by the shuttle, rotatable vane wheels passing through the warps into rolling contact with the pairs of rollers and adapted to support said shuttle from one side of the warps, means to prevent the vane wheels making rubbing contact with the shuttle body, a circular race extending round the loom on the other side of the warps and adapted to support said shuttle from that side of the warps, and a roller mounted in the shuttle for engagement through the warps by said circular race. 5

6. A circular loom comprising, in combination with a source of supply of warps, a shuttle, pairs of flanged rollers carried by the shuttle, rotatable vane wheels passing through the warps into rolling contact with said flanged rollers and adapted to support said shuttle from one side of the warps, the flanges of said rollers preventing said vane 20 wheels from making rubbing contact with the shuttle body, a circular race extending round the loom on the other side of the warps and adapted to support said shuttle from that side of the warps, and a roller mounted in the shuttle for 25 engagement through the warps by said circular race.

7. A shuttle for a circular loom of the type in which a shuttle is positioned in the warp shed on the one side by rotatable vane wheels which 30 pass through the warps into engagement with the shuttle and on the other side by a circular race extending round the loom and engaging the shuttle through the warps, said shuttle comprising a top plate, an intermediate plate, a spool-supporting bracket connecting said plates, a further plate extending from said intermediate plate to the fell of the fabric being formed, roller-bearing means mounted substantially vertically in said further plate for engagement through the warps 35 on one side of the shuttle by the circular race, horizontal bearings mounted at different levels in said further plate, two spindles mounted in said bearings, and flanged rollers mounted on said spindles for engagement on the other side of the 40 shuttle by the vane wheels. 45
